UNITED STATES PATENT OFFICE

EDGAR A. TERRELL, OF CHARLOTTE, NORTH CAROLINA

BOBBIN STRIPPER

Application filed November 15, 1928. Serial No. 319,537.

The invention has relation to machines of the class used in the textile industry for the purpose of stripping so-called feeler-waste, i. e., residues of weft or filling, from bobbins that have been expelled from the working shuttle of an automatic weft-replenishing loom in the performance of bobbin-changing operations brought about under the control of a so-called weft or filling-feeler. More particularly, it relates to bobbin-stripping machines of the type having blades or the like by which the residue of weft or filling remaining on an expelled bobbin is removed from the bobbin-barrel by a scraping action taking place lengthwise along the bobbin-barrel.

The invention comprises improvements conjoined with an inclined guideway or chute along which bobbins requiring to be stripped pass on their way from a supply-hopper to the stripping devices; novel means at the bottom of said inclined bobbin guideway or chute for supporting a bobbin in proper relations with respect to the stripper-devices; and for delivering the bobbin to the stripper-devices and cooperating bobbin-pusher and bobbin-puller elements including novel and improved features.

The accompanying drawings illustrate the features of the invention applied in a bobbin stripping machine of the type aforesaid embodying certain of the general principles of the machines of U. S. Letters Patent for bobbin stripper, No. 1, 349,448, granted August 10, 1920, upon application of G. B. Bahan & A. St. Onge; and of U. S. Letters Patent for bobbin strippers, No. 1,514,924, granted November 11, 1924, upon application of George J. Pfeiffer and No. 1,515,880, granted November 18, 1924 upon application of said Pfeiffer.

In the drawings,—

Fig. 1 is a view of the said machine in side elevation with the bobbin guideway or chute

omitted, this being shown separately in Figs. 4, 5 and 6.

Fig. 2 is a plan view of the parts which are shown in Fig. 1.

Fig. 3 is a side view of the machine looking at the side thereof opposite that which is shown in Fig. 1, and with the bobbin guideway or chute in place upon the machine.

Fig. 4 is a view in side elevation of the bobbin guideway or chute detached, on a larger scale than Figs. 1 to 3, and with a portion of the length of the horizontally extending part of the guideway or chute omitted.

Fig. 5 is a view of the parts which are shown in Fig. 4, looking at the same from the right-hand side in Fig. 4.

Fig. 6 is a view in vertical section in the plane of line 6—6 of Fig. 4.

Fig. 7 is a plan view on a considerably enlarged scale of about half of the machine, including the end thereof at which are located the bobbin guideway or chute and the push-head by means of which a bobbin engaged thereby is pushed partway through between the stripper-blades. The bobbin guideway or chute is omitted.

Fig. 8 is a plan view on the same relatively enlarged scale showing the opposite end of the machine.

Fig. 9 is a view in side elevation of the gripper-jaw cross-head, this view being on a still larger scale.

Fig. 10 is a plan view of the said gripper-jaw cross-head.

Fig. 11 is a plan view of the said gripper-jaw cross-head with one of the cover-pieces omitted.

Fig. 12 is a view in side elevation of the assemblage including the detents or stops by means of which the rack of the gripper-jaws is actuated in the movements of the gripper-jaw cross-head.

Fig. 13 is a view in side elevation of the gripper-jaw cross-head, plus the assemblage

of Fig. 12, with the parts in their proper relative positions, the parts being viewed from the side opposite that shown in Figs. 9 and 12.

5 Fig. 14 is a view showing the gripper-jaw cross-head in vertical section in a plane located at midwidth of the gripper-jaw cross-head.

Having reference to the drawings,—

10 The machine shown in the drawings has a frame constructed with a bed 1 comprising two side-members, indicated in Figs. 2, 7, 8, having a spaced-apart parallel relation, with such bed supported upon legs 2, 2. Above 15 this bed is disposed in practice the bobbin-chute or guideway, 3, 4, which is shown in Fig. 3 in place upon the machine, and separately in Figs. 4, 5, 6, and which receives the bobbins that are supplied to the machine 20 for the purpose of being operated upon, and conducts them toward the stripping point in the machine. In practice, the bobbin-chute or guideway is so contrived and so disposed in the machine that a bobbin placed therein 25 will be conducted to the said stripping point and, after having been given a position in which its length extends horizontally lengthwise of the machine, will be deposited between the two opposing sets of stripper- 30 blades 5, 5, and 6, 6, Fig. 7, which preferably constitute the stripper-devices, with the rings on its head resting upon bobbin-rests 7, 7, at the front side of the stripper-blades. The 35 delivery-end of the bobbin-chute or guideway positions the bobbin so that when deposited between the two sets of stripper-blades, with its head in contact with bobbin-rests 7, 7, its tip end will be presented in readiness for being acted against by the traveling push- 40 head 8, so that the latter by a movement toward the front end of the machine may perform its function of pushing the bobbin lengthwise, head-end foremost, part way through between the stripper-blades, to 45 thereby cause the waste yarn that is on the bobbin to be moved by the stripper-blades from its normal position adjoining the bobbin-head to a portion of the bobbin-barrel near the tip thereof. The extent of the end- 50 wise movement of the bobbin produced by this action of the push-head is such as to to carry the bobbin-head into position to be grasped by the gripper-jaws 9, 9, Figs. 8 to 11, 13, 14, mounted on traveling pull-head 10, 55 so that by forward travel of the said pull-head, the remainder of the length of the bobbin may be drawn through between the gripper-blades, whereby to complete the removal of the waste yarn from the bobbin-barrel, 60 over the tip end thereof.

The bobbin-chute or guideway, comprises the horizontally extending portion 3 in which the bobbins carrying waste are deposited, and along which they are pushed by hand toward 65 the stripping mechanism, and the inclined

arc-shaped portion 4 down which the bobbins slide under the influence of gravity for delivery to the said mechanism. The said bobbin-chute or guideway is composed mainly of two cheek-plates 31, 31, and two chute-castings 32, 32, to which the said cheek-plates are attached. The said chute-castings serve as feet for the bobbin-chute or guideway. They are attached to the top surfaces of the opposite side-portions of bed 1, so that the bobbin-chute or guideway surmounts the push-head and its actuating mechanism, with the portion 3 of the bobbin-chute or guideway extending rearwardly as in Fig. 3. The chute-rails 33, 33, attached to the upper edges 70 of the cheek-plates 31, 31, at the inner faces of the latter, are spaced apart just sufficiently to permit the barrel of a bobbin to enter between them, but not sufficiently to admit the bobbin-head. A bobbin dropped into the 75 portion 3 of the bobbin-chute or guideway will be supported by its head resting upon the two chute-rails, with its barrel hanging down between the two cheek-plates. As the bobbin, when advanced by the attendant 80 upon the machine, moves along toward the stripper-mechanism the bobbin-head will move along the chute-rails and then pass by gravity down the arc-shaped portion of the bobbin-chute or guideway to the lower end of 85 such arc-shaped portion. Between the cheek-plates and below the chute-rails 33, 33, are located bobbin guide-strips 34, 34, which are 90 spaced apart just sufficiently to admit between them the small part of a bobbin-barrel 95 near its tip. These guide-strips determine the position of the bobbin-tip and barrel transversely, and prevent it from assuming a position inclined to one side or the other. They serve also to hold the barrels of successive 100 bobbins in line with one another, and to prevent one from lapping past another.

As one feature of invention I employ a segmental rack 35, Figs. 4 and 6, within the inclined arc-shaped portion 4 of the bobbin-chute or guideway. This segmental rack 35 is located below the guide-strips 34, 34, with the convex line of its teeth paralleling the chute-rails 33, 33. The said line of teeth is located at a distance from the chute-rails a 110 little less than the length of the bobbins which are operated upon, so that when a bobbin begins to descend the said arc-shaped portion of the bobbin-chute or guideway, with the bobbin-head in engagement with the 115 chute-rails, the bobbin-tip will encounter the first teeth of the rack, with the effect of detaining the bobbin-tip and thereby tilting the bobbin forward, so that the bobbin-head shall be in the lead. In the continued movement 120 of the bobbin around within the arc-shaped portion of the bobbin-chute or guideway the bobbin-tip will drag over the succession of rack-teeth, ensuring progressive tilting of the bobbin until, as the bobbin arrives at the 125 130

lower end of the arc-shaped portion 4, the bobbin extends horizontally, with the bobbin-length extending lengthwise of the machine.

5 The rack 35 has formed on its front edge, below the lowermost tooth of the segmental series of teeth, a narrow guiding surface 36, Figs. 4 and 6, inclining forward slightly toward its bottom end. The said surface 10 constitutes a guide down which the tip-end of a bobbin slips as the bobbin descends below the lower end of the arc-shaped portion of the bobbin-chute or guideway. It constitutes also one element of means for positioning the bobbin endwise in proper relation to the stripper-devices just prior to the entry of the bobbin between the opposing sets of stripper-blades.

15 A segmental guard 11 which overlies the convexity of the inclined arc-shaped portion of the bobbin-chute or guideway, and parallels such convexity, at a distance therefrom corresponding with the size of the heads of the bobbins operated upon, serves as an external guide for the bobbin-heads by which the bobbins are prevented from outward displacement during their passage down the said arc-shaped portion. It cooperates with the chute-rails 33, 33, in ensuring that at 20 the delivery-end of the said arc-shaped portion the bobbin shall be positioned so that in being discharged into position to be acted upon by the stripper-devices the bobbin-head shall come to rest upon the rests 7, 7, Fig. 7, 25 adjacent the stripper-blades, with the portion of the bobbin that adjoins the shoulder of the head presented properly to the acting ends of the stripper-blades, and with the tip-end of the bobbin in proper relation to the 30 bobbins-pushing surface 81, Fig. 7, of the push-head 8.

35 I provide means whereby a bobbin which has arrived at the lower end of the arc-shaped portion of the bobbin-chute or guideway is detained at a slight elevation relative to the stripper-devices and push-head, until the return of the push-head to starting position has carried the said bobbin-pushing surface 81 of the push-head beyond the tip-end of the 40 bobbin, in order that when the bobbin makes a further drop the said tip-end may pass down in front of the said pushing surface 81 and the adjoining portion of the bobbin-barrel may land in the concavity 82 of the 45 push-head, such concavity constituting a bobbin-tip seat. The said means comprises in the illustrated machine a bobbin-tip cradle, and a bobbin-head detent. The said cradle is constituted by a pair of fingers 12, 12, 50 Fig. 6, fixedly connected with small rock-shafts 121, 121, which are mounted in bearings provided in connection with the lower portion of the rack-piece. Each of these rockshafts has applied thereto a spring 122, 55 Fig. 4, whereby the rockshafts and cradle-

60 fingers are controlled so as to keep the cradle-fingers normally in positions in which they extend horizontally toward each other, as in Fig. 6, in readiness to receive and sustain the tip-end of a bobbin as it descends from the delivery-end of the bobbin-chute or guideway. The said bobbin-head detent is constituted by a lip 13, Fig. 4, upon the lower end of the segmental guard 11. The said lip 65 is curved toward the tip-end guiding surface 36 of the segmental rack-piece, and it acts with elastic pressure against the extreme end of the head of a bobbin so as to keep the extreme tip-end of the bobbin in engagement with surface 36. Thus the elastically-acting 70 curved lip serves to uphold the head-end while the cradle upholds the tip. The said elastic pressure may be produced by providing the curved lip 13 upon a flexible elastic piece 131 attached to the lower end of the 75 segmental guard 11, or upon a spring-controlled piece hinged to the said guard, or, it may be secured through mounting the segmental guard by means of a pivotal connection at 111, Fig. 4, between the upper end of 80 the guard and a bracket 112 attached to one of the chute-stands 32, and through connecting to the guard a contracting spiral spring 113 acting to hold the guard normally in a 85 predetermined position suitable for securing the results aforesaid through coaction with the end of the head of a bobbin. In the present instance the segmental guard is held from displacement sidewise by means of a guide-arm 114 attached thereto and extending rearward alongside one of the chute-stands 32, under a guide 115 attached to such chute-stand. The normal position of the 90 guard radially of the arc-shaped portion of the bobbin-chute or guide is fixed, with capacity for adjustment, by means of an adjustment screw 116 carried by guide-arm 114 and engaging with a surface on guide 115. The elastically-acting curved lip constitutes 95 a second element of means whereby the bobbin is positioned endwise in proper relation to the stripper-devices. In virtue of the guard 11 being hinged at 111 at its upper end, as described, it is capable of yielding so as to obviate breakage of parts in case through 100 the action of the push-head in pushing a bobbin through between the sets of stripper-blades such bobbin should be driven endwise head-end foremost, against the detent 13. Thereby injury to the bobbin is avoided.

105 I provide means whereby at the proper time a bobbin that is upheld at the lower end of the arc-shaped portion 4 of the bobbin-chute or guideway, by the cradle and the elastically-acting lip aforesaid, is disengaged from said cradle and lip so that it is rendered free to drop into place in relation to the stripper-devices and the push-head. Such means in the illustrated machine is constituted by a plunger 14, Figs. 4 and 5, oc- 110

cuping a guide-bearing at 15 in connection with a bracket 141 attached to one of the chute-stands 32, the guide-bearing and the plunger being located a little below the 5 mouth of the bobbin-chute or guideway. The said plunger is arranged to move longitudinally within the said guide-bearing in directions at right-angles with the length of a bobbin supported by the cradle and lip. The 10 outer end of the plunger is notched for engagement with a pin 143, Fig. 7, carried by an arm 142, Figs. 2, 3, and 7, in connection with the rockshaft 16 shown in such views at one side of the machine. The inner end of 15 the plunger is beveled at its under side so that when the rockshaft 16 is rocked in the direction to cause the plunger to move crosswise with relation to the mouth of the bobbin-chute or guideway, the wedge-shaped end 20 acts to force the said bobbin downward, thereby disengaging it from the cradle and curved lip and causing it to drop as mentioned. When the rockshaft is rocked 25 reversely the plunger is withdrawn so as to permit the next succeeding bobbin in the bobbin-chute or guideway to drop down upon the cradle and curved lip, in readiness to be 30 disengaged and dropped through the action of the bevel-ended plunger in its next working stroke.

As shown best in Figs. 2 and 7, the two sets of stripper-blades 5, 6, and 5, 6, extend transversely of the machine within guides projecting from the two side-portions of the bed 1. 35 The working ends of the blades of one set are spaced apart from those of the other set sufficiently to admit a bobbin between them. The two bobbin-rests 7, 7, are carried by the 40 said guides, with each of the said bobbin-rests alongside the working ends of the blades of the corresponding set, the pair of bobbin-rests being located forward of the stripper-blades so that the head of a descending bobbin may land upon the two bobbin-rests as the 45 portion of the bobbin that adjoins the head passes down between the two sets of stripper-blades.

The stripper-blades are actuated, to close their working ends inward against opposite 50 sides of a bobbin that has been dropped between the two sets, and subsequently to separate the two sets more widely for the reception between them of the next succeeding bobbin, by means of levers 51, 61, which are 55 combined operatively with the two rockshafts 16 and 161 extending alongside the other sides of the bed 1 and mounted in bearings, as 162, 162, attached to the bed. For the purpose of enabling the said rockshafts to be actuated 60 they are provided with arms 163, 163, engaging grooved cams 164, 164, upon the shaft 165 extending across the machine at the head-end thereof. In practice the construction, &c., providing for yielding action in closing 65 the two sets of stripper-blades together

against the opposite sides of a bobbin will be, preferably, as in my application for U. S. patent for improvement in bobbin-strippers filed November 14, 1928, Serial No. 319,284.

Following the action of the wedge-ended plunger 14 in dropping a bobbin from a position at the delivery-mouth of the bobbin-chute or guideway into stripping position with the bobbin-head resting upon the pair of bobbin-rests 7, 7, with the adjoining portion of the bobbin between the two sets of stripper-blades and the bobbin-tip resting in the tip seat 82 of the push-head 8, and after the ensuing closing of the working ends of the stripper-blades against the bobbin, the push-head is moved in the direction from the head-end of the machine toward the foot-end thereof so as to push the bobbin lengthwise part-way through between the stripper-blades. This results in the waste yarn being stripped by means of the said blades from the portion of the bobbin-length which thereby is pushed past the stripper-blades. Simultaneously with this movement of the push-head 8 the pull-head 10 is advanced in the reverse direction, namely in the direction from the foot of the machine toward the stripper-blades, so as to meet the advancing bobbin-head and present the gripper-jaws 90 for engagement therewith. As soon as the bobbin-head is fairly within the engaging portions of the gripper-jaws the latter are closed upon the bobbin-head, grasping the latter. At this time the movements of the push-head and pull-head are reversed. The push-head returns empty to starting position, and the pull-head returns to the foot of the machine, carrying the bobbin with it, so as to effect complete withdrawal of the bobbin through between the stripper-jaws, thereby completing the clearing of the waste yarn from the bobbin-barrel.

The push-head 8 and pull-head 10 are supported by guides 82, 82, and 102, 102, in connection with the opposite side-portions of the bed 1, and they respectively are connected by pitmen 83 and 103 to cranks 84 and 104 in connection with, respectively, the transverse shaft 165 at the head-end of the machine, and the transverse shaft 105 at the foot-end of the machine. Through these actuating connections the push-head and pull-head are actuated simultaneously in opposite directions with respect to each other, so that the push-head and pull-head simultaneously approach the stripper blades in opposite directions, and simultaneously recede therefrom in opposite directions.

The bobbin-pushing surface 81 with which the push-head is furnished may advantageously be constituted by a block of lead or other material not likely to bruise or otherwise injure the bobbin-tips against which it acts, and may be detachably attached to the 125

push-head, for example by means of screws 86, as shown, to enable it to be replaced when replacement is found to be advisable.

Opening and closing movements of the gripper-jaws 9, 9, are provided for by mounting them upon vertical pivots 91, 91, Figs. 8, 9, 10, 11, 13, on the pull-head 10, so as to have capacity to swing horizontally toward and from each other. For the actuation of the gripper-jaws so as to produce such movements they have combined with them a rack-bar 92, Figs. 10, 11, 14, which is mounted in a guide 93 upon the pull-head so as to be movable endwise lengthwise of the strokes of the pull-head. As shown in Fig. 11, this rack-bar is provided with teeth 94, 94, upon opposite sides thereof and the hubs 95, 95, of the gripper-jaws are formed with teeth 96, 96, with which the teeth 94, 94, of the rack-bar are engaged. Through the described toothed engagement of the rack-bar with the two gripper-jaws, endwise movement of the rack-bar within the guide 93 on the pull-head will occasion swinging movement of the gripper-jaws around their pivots 91, 91.

I provide stops 17, 17, Figs. 12 and 13, for the purpose of producing endwise shift of the rack-bar relative to the pull-head, first in one direction as the pull-head nears the completion of its stroke away from the stripper-blades, so as to open the gripper-jaws to release a stripped bobbin that is clasped thereby, and also in order to prepare for engagement of the gripper-jaws with a succeeding bobbin, and afterwards in the opposite direction as the pull-head completes its stroke toward the stripper-blades, so as to close the gripper-jaws upon the head of a bobbin that has been advanced part-way through the stripper-blades by the pushing action of the push-head. The said stops are carried by a bracket 18 which is mounted upon bed 1 and extends over the pull-head. A post 97 rising from the rack-bar 92 encounters the said stops in the reciprocating movements of the pull-head. The stops extend down from the over-arching portion of bracket 18 into the path of the said post. During movement of the pull-head in a given direction, encounter of the post 97 with a stop 17 arrests the rack-bar, while the pull-head continues a short distance farther, the result of which is to occasion relative displacement between rack-bar and pull-head whereby the gripper-jaws are actuated to open, or close, as the case may be. In this manner, the gripper-jaws are caused to open as the pull-head approaches the limit of its movement away from the stripper-blades, and are caused to close as the pull-head in its return movement nears the stripper-blades.

I provide means for locking the gripper-jaws in their closed condition, as soon as they have closed upon a bobbin-head at the end of their movement toward the stripping blades,

and for keeping them locked during the movement of the pull-head away from the stripper-blades. The lock in the present instance is constituted, essentially, by a bell-crank 19, shown best in Fig. 14, occupying a vertical slot in the post 97 and mounted upon a horizontal pivot 191 in connection with the said post, so that the locking bell-crank is adapted to swing in a vertical plane. One arm of the bell-crank extends upward from the pivot, while the other arm thereof extends horizontally toward the stripper-blades and, as shown best in Fig. 14, under a bar 192 extending across from one jaw-pivot 91 to the other as shown best in Fig. 10. An expanding spiral spring 20, Figs. 13 and 14, acts against the bell-crank with a tendency to rock the latter so as to raise the extremity of the horizontal arm thereof against the underside of the said bar 192 and also cause the back of the up-standing arm of the bell-crank to project as shown at the front side of the post 97. The said extremity of the horizontal arm is notched to receive the cross-bar 192 and provide a shoulder which, when the rack-bar occupies the advanced position relative to the push-head in which it is shown in Fig. 14, will, through engagement with the front of the bar, hold the rack-bar forward and the gripper-jaws closed, as well as to provide a toe which through engagement with the underside of the cross-bar will limit the rise of such arm. Thereby the locking of the gripper-jaws in a closed condition in engagement with a bobbin-head is accomplished.

The unlocking of the gripper-jaws at the extreme limit of the bobbin-withdrawing movement of the pull-head, to permit relative movement between the pull-head and the rack-bar to occasion the opening of the gripper-jaws, results from contact of the projecting back of the up-standing arm of the bell-crank with the appropriate stop 17, whereby the bell-crank is rocked upon its pivot so as to depress its horizontal arm and thereby disengage the notched end of such arm from the cross-bar. As now the post 97 engages with the said stop the latter holds the rack-bar stationary while the pull-head completes the short remainder of its movement. The resulting relative movement of the pull-head with respect to the rack-bar will cause the cross-bar to pass over the horizontal arm of the bell-crank, to an intermediate position between its notch and the fulcrum 191 of the bell-crank. The said relative movement will result in the opening of the gripper-jaws and they will remain open until in the movement of the pull-head toward the stripper-blades the post 97 engages with the other stop 17. The effect of such engagement is to arrest the rack-bar, producing the relative shift which occasions the opening of the jaws 9, 9. As soon as this relative shift has disposed the cross-bar 192 in position to oc-

cupy the notch in the extremity of the horizontal arm of the bell-crank spring 20 will turn the latter on its fulcrum so as to carry the toe of the said arm up against the underside of the cross-bar and the shoulder adjoining said toe up alongside the cross-bar, thereby locking the jaws in open condition. To ensure against any accidental shift in the position of the rack-bar with reference to the pull-head during this movement, I provide a yielding detent constituted by a ball-shaped plunger 98, Fig. 14, acted upon by an expanding spiral spring 981 and adapted to enter a recess 982 in the underside of the rack-bar.

In order to enable the stops 17, 17, to yield slightly when acted against by the post 97, each thereof is carried by a plate 171 mounted on the top of the bracket 18, the blocks on which the stops are formed working in slots 173, 173, in the top of the said bracket and being engaged with the plates 171, 171, by bolts 172, 172. A longitudinally extending bolt 174 engaged with an upstanding portion of one of the plates 171 extends through a hole in an upstanding portion in the other of the said plates and receives beyond its stem upon the latter upstanding portion an expanding spiral spring 175 which is confined 25 between the said latter upstanding portion and a washer and nut 176 upon the screw-threaded extremity of the bolt. When either stop is acted against by the said post, the spring 175 yields. The minimum distance between the two stops is determined by means of 30 a collar 177 upon the stem of the bolt 174 between the two upstanding portions of the plates 171, 171.

Provision is made for adjustment of the 40 rack-segment 35 of the arc-shaped portion of the bobbin-chute or guideway to suit different lengths of bobbins. Thus the said rack-segment is mounted in connection with one of the chute-castings 32 with capacity for being set at different distances horizontally from the curved portions of the chute-rails 33, 33. In the present instance, the rack-segment is supported in connection with the said chute-casting by means of a lateral flange 351, 45 projecting therefrom into a horizontally extending slot 352 in the chute-casting, a bolt 353 being employed to fix the rack-segment in the required position. By shifting the rack-segment either forward or rearward as 50 permitted by the slot, the acting edge of the rack-segment may be positioned at a distance from the curved portions of the chute-rails 33, 33, suitably to the length of bobbin operated upon, and with the guide-surface 36 55 spaced from the lower end of the segment-guard 11 at a distance corresponding to the said length.

What is claimed as the invention is:

1. In a bobbin-stripper machine, the combination with a bobbin-stripper device, and

means for producing relative movement between said device and a bobbin presented thereto to be stripped, of a bobbin-chute having an arc-shaped delivery portion from which a bobbin to be stripped is delivered in a horizontally extended position with the bobbin-length extending lengthwise of the direction of said movement, and a segmental rack in connection with said arc-shaped portion having its teeth in the path of the bobbin-tip and adapted to act to progressively overturn a descending bobbin into the said horizontally extended position. 70

2. In a bobbin-stripper machine, the combination with an inclined bobbin-chute, of a tip-cradle at the discharging end of said chute comprising opposite rocking cradle-members, and means for applying spring-tension for yieldingly holding said members in bobbin-receiving position. 80

3. In a machine for operating upon bobbins, the combination with a reciprocating head, of a pair of gripper-jaws combined therewith, a bar movable longitudinally upon the said head and engaging with the said gripper-jaws to move the latter relative to each other when the bar is moved longitudinally, and stops in the path of the bar by which it is shifted relative to the head as the latter reciprocates. 95

4. In a bobbin-handling machine, the combination with a reciprocating head, of a pair of gripper-jaws pivotally connected to said head, a longitudinally movable bar engaging with said gripper-jaws, and stops in the path of said bar to shift it relative to the head to open and close the gripper-jaws. 100

5. In a bobbin-stripper machine, the combination with a reciprocating pull-head, of a pair of gripper-jaws pivotally connected to said head, a longitudinally movable bar engaging with said gripper-jaws, stops in the path of said bar to shift it relative to the head to open and close the gripper-jaws, and a lock which retains the gripper-jaws closed 105 during the bobbin-pulling movement and releases the same at the conclusion of such movement. 110

6. In a bobbin-stripper machine, the combination with a pull-head, of a pair of gripper-jaws pivoted thereto, a longitudinally movable bar on said head engaging with said gripper-jaws, stops which act through engagement with a projection from said bar to produce relative movement between the bar and the pull-head, and a lock by which said bar is locked with the gripper-jaws closed during the bobbin-pulling movement, said lock disengaged through disengagement with one of the said stops. 115

7. In a bobbin-stripper machine, the combination according to claim 1 characterized by a segmental rack which is adjustable to suit different lengths of bobbins. 120

8. In a bobbin-stripper machine, the com- 125

bination according to claim 3 characterized by yielding stops for the bar.

9. In a bobbin-stripper machine, the combination according to claim 4 characterized by longitudinally movable spring-controlled 5 yielding stops for the bar.

10. In a bobbin-stripper machine, the combination with a bobbin-stripper device, and means for producing relative movement between said device and a bobbin presented thereto to be stripped, of a bobbin-chute having an inclined delivery portion, a guide-surface for the end of the tip of a bobbin, a detent which engages with the extremity of the bobbin-head and positions the bobbin lengthwise with its tip-end against the said guide-surface, and means for discharging the bobbin from said guide-surface and detent to the bobbin-stripper device.

20. 11. In a bobbin-stripper machine, the combination with a bobbin-stripper device, means for producing relative movement between such device and a bobbin delivered thereto, in a direction lengthwise of the bobbin, and an 25 inclined bobbin-chute having a guide-surface for the end of the tip of a bobbin, of a tip-craddle, a head-detent at the delivery end of such chute which positions the bobbin lengthwise with its tip-end against the said guide- 30 surface, and means for discharging a bobbin from the said tip-craddle and head-detent to the bobbin-stripper device.

12. In a bobbin-stripper machine, the combination with a bobbin-stripper device, a 35 bobbin-head rest at one side thereof, a push-head at the other side thereof adapted to push a bobbin endwise relative to the said bobbin-stripper device through engagement with the bobbin tip, an inclined bobbin-chute having 40 a guide-surface for the end of the tip of a bobbin, yielding bobbin-tip detents at the delivery-end of said bobbin-chute, a head-detent at said delivery-end which positions the bobbin lengthwise with the end of its tip against 45 the said guide-surface, and means for forcing a bobbin past the said detents to present its head to the bobbin-head rest and its tip to the push-head.

13. In a bobbin-stripper machine, the combination with a bobbin-stripper device, a bobbin-head rest at one side thereof, a pull-head at the same side with said bobbin-head rest, a push-head at the other side of the bobbin-stripper device adapted to push a bobbin endwise relative to the bobbin stripper device through engagement with the bobbin-tip and thereby present the bobbin-head in position to be engaged by the pull-head, an inclined bobbin-chute, detents at the delivery end of 55 said bobbin-chute for the tip and head of a bobbin, and means for discharging positively a bobbin from said detents to present its head to the bobbin-rest and its tip to the push-head.

60 14. In a bobbin-stripper machine, the com-

bination with stripper-blades, means for moving a bobbin endwise therethrough, and an inclined bobbin-chute, of a guard covering said chute hinged at its upper end to a support therefor, and capable of yielding in 70 case a bobbin should be forced thereagainst.

15. In a bobbin-stripper machine, the combination with a bobbin-stripper device, and an inclined bobbin-chute, of a tip-cradle and a head-detent at the delivery end of said chute, said head-detent operating to position a bobbin lengthwise, and a reciprocating plunger having a wedge-shaped acting portion which forces the bobbin from said tip-cradle and head-detent to the bobbin-stripper 80 device.
